UNITED STATES PATENT OFFICE.

WILHELM HILDEBRAND, OF BERLIN, GERMANY, ASSIGNOR TO HANDEL-MAAT-SCHAPPIJ H. ALBERT DE BARY & CO., OF AMSTERDAM, NETHERLANDS.

VALVE FOR SINGLE-CHAMBER AIR-PRESSURE BRAKES.

Application filed April 10, 1923. Serial No. 631,141.

To all whom it may concern:

Be it known that I, WILHELM HILDEBRAND, a citizen of the German Republic, residing at 9-17, Neue Bahnhofstrasse, 5 Lichtenberg O. 112, Berlin, Germany, have invented certain new and useful Improvements in Valves for Single-Chamber Air-Pressure Brakes, of which the following is a specification.

10 This invention relates to valves for single chamber air pressure brakes, its object being to provide in addition to the graduated increase of the braking action means for obtaining a graduated reduction thereof, that 15 is to say, a step by step release of the brake, while avoiding the difficulties arising from the division of the auxiliary air reservoir into two chambers by a braking piston of large diameter and frictional resistance as 20 described in the prior United States patent specification No. 1,425,477.

According to this invention a regulating container divided into two chambers of variable capacity is inserted into the connection between the train pipe and the auxiliary air reservoir, and in the said container is provided an easily working piston mounted on a common piston rod with a smaller counter piston working in a guide 30 tube or recess. The chamber in which the counter piston is located is connected with the chamber of the brake filling valve, and the other chamber of the regulating container is in direct communication with the auxiliary reservoir, and in communication 35 through the said filling valve with the train pipe.

In order that the said invention may be clearly understood and readily carried into effect, the same will now be described more fully with reference to the accompanying drawings, in which:—

Figure 1 shows diagrammatically the apparatus in the release position.

Figure 2 shows the same apparatus in the position assumed when applying the brake.

The reference letter *e* indicates the train pipe, *b* the chamber of the brake and release distributing valve *i*, *c* the brake cylinder, *a* the auxiliary air reservoir, all arranged in known manner, except that there is no filling groove passing round the piston of the distributing valve chamber *b* in the release position, because the filling of the brake cylinder is effected through the pipe *o* from the

auxiliary reservoir *a* when the valve *i* is in the position shown in Figure 2, the valve *p* in the valve chamber *d* then closing the connection between the brake cylinder *c* and the open air through the recess *n* in the valve *i*, the pipe *m*, and the recess *k* in the said valve *p*. When the brake is to be taken off this connection is re-established by the return of the valves *i* and *p* to the positions shown in Figure 1, when the pipe *q* connects the train pipe *e* through the recess *l* in the valve *p*, the pipe *r*, and the chamber *t* of the regulating container *f*, with the auxiliary air reservoir *a*. The chamber *s* of the regulating container *f* contains a differential piston comprising a larger piston *g* and a small counter piston *h*, this chamber *s* being constantly in communication with the interior of the casing *d* of the filling valve *p*. In the normal position shown 75 in Figure 1 pressure in the chambers *s* and *t* is equalized through a filling groove adjacent to the piston *g*.

When the pressure in the train pipe *e* is reduced to apply the brake, the pistons of 80 the valves *i* and *p* will pass into the positions shown in Figure 2, when air from the reservoir *a* acts on the piston in the brake cylinder *c*, the connection between the pipes *r* and *q* is interrupted and the reduction of 85 pressure in the reservoir *a* and chamber *t* allows the piston *g* to move to the left beyond its filling groove *w*, the counter piston *h* of course partaking in this movement. If the pressure in the train pipe *e* has only 90 been slightly reduced so that in these movements the pressure in the auxiliary reservoir *a* falls below that in the train pipe, the distributing slide valve *i* will be forced back into the release position, but the connection 95 between the brake cylinder *c* and the open air is not re-established because the filling slide valve *p* remains in the "brake on" position owing to the pressure in the chamber *s* being maintained by the movement of the 100 counter piston *h* at a higher level than that in the chamber *t*. By a further reduction of the pressure in the train pipe the slide valve *i* can again be brought into the "brake on" 105 position to place the auxiliary reservoir in communication with the brake cylinder.

For the purpose of obtaining a graduated release of the brakes, the pressure in the train pipe is so much increased that it somewhat exceeds the pressure in the auxiliary 110

reservoir. The distributing valve *i* and filling valve *p* then pass into the release position, so that the air begins to escape from the brake cylinder, but at the same time the chamber *t* of the regulating container is connected with the train pipe *e* through the pipe *g*, recess *l* and pipe *r*, hence the pressure in the chamber *t* increases and forces the differential piston *g h* to the right, causing a pressure in the chamber *s* which, owing to the presence of the counter piston *h* exceeds the train pipe pressure and the valve *p* is thus forced downward, whereby the releasing process is stopped and the release 10 cut-off position induced. In order to effect the complete release of the brake the full train pipe pressure is restored, which causes the distributing valve *i* to return to the release position and the valve *p* to return to 15 the filling position. The train pipe pressure extending to the chamber *t* of the regulating container *f* at the same time causes the differential piston *g h* to recede to its extreme right hand position, in which a filling groove 20 *w* becomes operative to bring about an equipoise of pressure at both sides of the piston *g*.

What I claim and desire to secure by Letters Patent of the United States is:—

1. In a single chamber compressed air 25 brake, a train pipe, an auxiliary air reservoir, a brake cylinder, a connection between said reservoir and said cylinder, a connection between said cylinder and the atmosphere, a distributing valve controlling both

said connections, a regulating container 35 comprising two chambers of variable capacity divided by a reciprocable differential piston, one of said chambers being connected with said reservoir and said train pipe, and a filling valve adapted to control the connection between said chamber and said train pipe and also to control the connection between said cylinder and the atmosphere, said piston being adapted to control the movements of said filling valve. 40 45

2. Distributing means for single chamber compressed air brakes characterized by the facts that a controlling device is provided for applying and releasing the brake and another controlling device is provided for filling the brake, and that for the purpose of permitting a graduated release between the auxiliary air reservoir and the filling control device there is provided a regulating container having a differential piston, in 50 which container the chamber at one side of the larger piston is connected with the said auxiliary air reservoir and with the train pipe, while this latter connection is interrupted by the filling control valve upon 55 application of the brake, while the chamber at the other side of the separating piston of the regulating container situated towards the counter piston is connected with the distributing slide valve chamber of the filling 60 control valve. 65

WILHELM HILDEBRAND.
